UNITED STATES PATENT OFFICE.

GUSTAV ADOLF UNTERBERG, OF DURLACH, GERMANY.

CONTACT-BREAKER FOR MAGNETO-ELECTRIC IGNITING APPARATUS.

981,599.

Specification of Letters Patent. Patented Jan. 10, 1911.

Application filed April 20, 1909. Serial No. 491,135.

To all whom it may concern:

Be it known that I, GUSTAV ADOLF UNTERBERG, a citizen of the German Empire, and resident of Durlach, Baden, German Empire, have invented certain new and useful Improvements in Contact-Breakers for Magneto-Electric Igniting Apparatus, of which the following is a full, clear, and exact description.

10 The present invention relates to contact breakers for magneto-electric igniting apparatuses for explosive power motors.

The invention relates more particularly to the particular arrangement of the breaker 15 spring and the movable contact, which latter is not, as heretofore, mounted on the spring itself but on a separate lever adapted to swing out on a fulcrum, as hereinafter particularly set forth.

20 In order to render the present specification easily intelligible reference is had to the accompanying drawing in which similar letters of reference denote similar parts throughout the several views.

25 Figure 1 is a sectional view of the device taken along the line A—A of Fig. 2, Fig. 2 is a cross section on the line B—B of Fig. 1 and Fig. 3 is a vertical cross section taken along the line C—C of Fig. 1.

30 The breaker may be connected to the igniting apparatus in any known manner, the latter which is known and forms no part of the present invention not being shown in the drawing. For the purposes of the present specification the breaker is assumed to be mounted on the end a' of the armature shaft a of the magneto igniting device. The breaker spring, which exercises pressure in the direction of the axis a , consists of two 35 semicircular pieces b backwardly bent round at b'' (Fig. 3) and having their ends b' clamped to the shaft a' by means of the insulating disks c . The lever e carrying the movable contact d is mounted in front of 40 the springs b , the said lever being adapted to swing in the direction indicated by the arrow in Fig. 2, on the pin g which is supported against the non-yielding arm f .

The device operates in the following man-

ner:—When the breaker rotates, the lever e strikes the cam surface h with its extended end e' , the said cam h pushing the movable contact d off the stationary contact i and momentarily breaking the circuit. As soon as the cam h has been passed the spring b again forces the contacts d i together. By means of the hereinbefore described arrangement of the spring it is subjected to but very slight wear and tear and thus the life of the spring is prolonged. The pin i is mounted on the lever f and connected to one pole or terminal, but insulated from the pin g so that the circuit will be broken when the parts d and i are separated.

I claim as my invention:—

1. In a contact breaker for magneto electric igniting apparatuses, having a non-yielding lever carrying a stationary contact, a movable contact and means for supporting the same, the combination of springs 70 for normally holding the movable contact against the stationary one, consisting of two semicircular pieces having their ends bent round backwardly, a magneto shaft and two insulating disks to clamp the ends of the 75 said pieces to the said magneto shaft substantially as described.

2. In a contact breaker for magneto electric igniting apparatuses having a non-yielding arm supporting a stationary contact, 80 the combination of a yielding lever having a movable contact at one end and having its opposite end supported against the said non-yielding lever, a spring, consisting of two semi-circular pieces having their ends bent 85 backwardly, a magneto shaft and two insulating disks to clamp the said ends to the said magneto shaft, said spring serving to normally hold the movable contact against the stationary one and means for periodically 90 raising the former from the latter.

In testimony whereof I affix my signature in the presence of two witnesses.

GUSTAV ADOLF UNTERBERG.
